US0D1072822S

(12) **United States Design Patent** (10) Patent No.: **US D1,072,822 S**
(45) Date of Patent: ** Apr. 29, 2025

(54) **DATA CAPTURE DEVICE**

(71) Applicant: **ZEBRA TECHNOLOGIES CORPORATION**, Lincolnshire, IL (US)

(72) Inventors: **Huang Chih Huang**, Taoyuan (TW); **Steven D. Sieckowski**, Port Jefferson, NY (US); **Roland Wing Fai Lee**, Jericho, NY (US)

(73) Assignee: **Zebra Technologies Corporation**, Lincolnshire, IL (US)

(**) Term: **15 Years**

(21) Appl. No.: **29/896,198**

(22) Filed: **Jun. 29, 2023**

Related U.S. Application Data

(63) Continuation of application No. 29/781,760, filed on Apr. 30, 2021, now Pat. No. Des. 994,668.

(51) **LOC (15) Cl.** **14-02**

(52) **U.S. Cl.**

USPC **D14/428**

(58) **Field of Classification Search**
